US00D506730S

(12) **United States Design Patent** (10) Patent No.: **US D506,730 S**
(45) Date of Patent: **** Jun. 28, 2005**

(54) **BOARD-TO-BOARD CONNECTOR**

(75) Inventor: **Takahiro Ura**, Kanagawa (JP)

(73) Assignee: **Iriso Electronics Co., Ltd.**, Kanagawa (JP)

(**) Term: **14 Years**

(21) Appl. No.: **29/197,408**

(22) Filed: **Jan. 15, 2004**

(30) **Foreign Application Priority Data**

Aug. 29, 2003 (JP) 2003-025246

(51) LOC (8) Cl. **13-03**

(52) U.S. Cl. **D13/147**

(58) Field of Search D13/147; 439/74,
439/83, 108, 607, 660
